[57] **CLAIM**

The ornamental design for a bar linkage assembly for use with a padlock for securing a bicycle wheel, as shown and described.

DESCRIPTION

FIG. 1 is a top, front, and right side perspective view of a bar linkage assembly for use with a padlock for securing a bicycle wheel showing my new design, the bottom being a mirror image of the top, and the rear and left side being identical in appearance to the front;

FIG. 2 is an enlarged top, front, and right side perspective view thereof, showing the linkage assembly in a folded configuration; and,

FIG. 3 is a further enlarged, fragmentary, top, front, and right side perspective view of the pivot joint of the front and left side elements.
